UNITED STATES PATENT OFFICE.

WILLIAM T. BRIDGES, OF LA FAYETTE, GEORGIA.

FIRE ALARM.

Original application filed May 8, 1923, Serial No. 637,527. Divided and this application filed May 15, 1924. Serial No. 713,538.

This invention relates to a fire alarm system, which is especially adapted to be installed in a building, and is operable electrically upon the occurrence of fire to sound 5 an alarm.

The present application is a division of an earlier application, Serial Number 637,527, filed May 8, 1923.

The general object of the invention, as 10 herein claimed, is to provide a system which includes one or more local signals, such as an electric bell operable by a current of low voltage obtained by the interposition of a transformer between the same and the service wires, and, in combination therewith, a 15 loud alarm such as a siren, which may be mounted outside the building and operated by the service current, usually of 110 volts, the circuit through the siren being closed immediately upon the actuation of the local alarm.

The above and other objects and advantages of the invention will be more fully explained in the detailed description which 25 follows, in conjunction with the accompanying drawing, which illustrates the preferred form of the invention.

In the drawing:

Figure 1 is a diagrammatic view showing 30 the arrangement of the circuits used in connection with the installation of the invention.

Figure 2 is a detail view, partly in section, of the circuit closer for the high voltage circuit.

Figure 3 is a sectional view taken on the line 3—3 of Figure 2.

Figure 4 is an elevation of the circuit closer shown in Figure 2 looking from the 40 inside.

Figure 5 is a detail sectional view of a circuit closer, which may be used in connection with the low voltage circuit.

In carrying out the invention, main lead 45 wires 9 and 10 are connected to the service wires 11 and 12 respectively, and lead through a transformer 13 to various circuit closers 14 located in various parts of the building, which are so constructed that they 50 will be closed when fire occurs in the vicinity. One of the lead wires, as 9, is connected with a local alarm, such as an electric bell 15, which is adapted to be rung immediately upon the closing of the circuit 55 through the wires 9 and 10.

A second circuit 16, adapted to carry the same voltage as the service wires is connected with a siren 17 located outside the building in position to give a general alarm. The circuit 16 is normally open, but is adapted 60 to be closed by a circuit closer 18 as soon as the bell 15 begins to ring.

The circuit closer 18, as shown in detail in Figures 2, 3 and 4, includes a cup shaped housing 19, having a flanged rim 20 provided with notches 21 through which the wires of the circuit 16 may pass, and secured to the wall of the building by suitable screws 22, or the like. Fitting within the housing 19 is a supporting plate 23 having outturned 70 ends 24, which are secured to the rim 20 by inturned ears 25 cut from said rim. An insulating block 26 is secured to the central portion of the plate, by means of inturned ears 27 cut from the plate. Binding posts 75 28 and 29 are threaded into the block 26, and the open ends of the circuit 16 secured thereto. The binding posts 28 and 29 extend through openings 30 in the plate 23, and one of them, as 28, has a switch 31 pivoted thereto. This switch extends from its pivot normally above the other binding post 29 through a slot 32 in the housing 19, and its outer end 33 is composed of non-conductive material, and has a depending lug 34. The 80 bell 15 is so located that its clapper 35 extends underneath the outer portion 33 of the switch, and is oscillated downwardly and laterally when the bell is sounded. An expansile coiled spring 36 normally rests at 90 its lower end on the clapper 35, while its upper end receives the depending lug 34 and holds the switch open, as shown in Figure 2. When the bell circuit is closed and the bell clapper vibrates rapidly, the spring 36 95 is jarred therefrom and releases the switch 31, which swings by gravity into contact with the binding post 29, and closes the circuit 16 and sounds the siren 17.

The circuit closers 14 may be of any approved construction, such that they will be closed when fire occurs in their vicinity. The preferred construction is illustrated in Figure 5, which shows a cup shaped housing 37, in which an insulating block 38 is 100 supported in the same manner as the block 26 in the housing 19. Binding posts 39 are secured in the insulating block 38, and the wires 9 and 10 are connected thereto. The 105 ends of these binding posts 39 constitute 110

spaced contact members, by the bridging of which a circuit is established through the bell 15. The housing 37 is formed centrally with a perforation surrounded by an inner turned flange 40, within which is seated a movable contact member 41. This contact member has a cup shaped portion 42 which projects outwardly of the housing 37, and is normally held by a retaining pin 43. The inner portion of the member 41 is provided with a flat peripheral flange 44, which is adapted when released to bridge the contact members 39. An expansile coiled spring 45 is seated within the housing 37 surrounding the flange 40 and presses against the flange 44, urging it toward the contact members 39. The pin 43 is made of celluloid, lead or any other material, which will be fused or burned when subjected to fire. Consequently, when fire occurs, the pin 43 will be destroyed, thus releasing the movable member 41, which under the action of the spring 45 will be urged into position to bridge the contacts 39 and establish a circuit through the bell 15. As soon as the bell begins to ring, the switch 31 is released and is closed by gravity, and the siren 17 is sounded.

It will be understood that any number of circuit closers 14 may be located throughout the building, and upon the occurrence of fire in the vicinity of any one of them, the circuit through the bell 15 will be closed, and the siren, as well as the bell, immediately sounded.

While I have shown and described specifically the detailed construction of one form in which the invention may be carried out, it is to be understood that this is merely illustrative, and that various modifications

may be made therein as long as such modifications do not constitute a material departure from the salient features of the invention.

What is claimed is:

1. In a fire alarm system of the class described having an electric bell therein provided with an oscillatable clapper, a circuit closer associated with the clapper comprising a pair of terminals; a switch arm pivotally connected to one of the terminals and normally held spaced above the other terminal and operable by gravity when released to engage the other terminal; and spring means interposed between the bell clapper and the free end of the switch to hold the latter open, said spring being loosely held so as to be jarred loose by the vibration of the bell clapper to close the switch. 45

2. In combination with the oscillatable clapper of an electric bell of a fire alarm system, a circuit closer comprising a housing; a pair of terminals in the housing; a switch pivotally connected to one of said terminals and extending outwardly through a slot in the housing, the free end of said switch being spaced above the bell clapper and also the other terminal; means normally interposed between the clapper and the switch and supporting the latter in open position; said means being loosely held so as to be jarred loose by the vibration of the bell clapper when said clapper is actuated to permit the switch to fall by gravity and engage the other terminal. 60 65

In testimony, that I claim the foregoing as my own, I have hereto affixed my signature.

WILLIAM T. BRIDGES. 75
